UNITED STATES PATENT OFFICE.

CHARLES H. CRUMP, OF BOSTON, MASSACHUSETTS, ASSIGNOR TO WILLIAM E. BAKER, OF SAME PLACE.

DESIGN FOR A GRAPE-ARBOR.

Specification forming part of Design No. 6,962, dated October 21, 1873; application filed September 29, 1873.
[Term of Patent 7 years.]

To all whom it may concern:

Be it known that I, CHARLES H. CRUMP, of Boston, of the county of Suffolk and State of Massachusetts, have invented or produced a new ornamental Design for a Vinarium; and do hereby declare the same to be fully described in the following specification and represented in the accompanying drawing, which is a perspective view of such article having the shape or configuration constituting my said design.

In carrying out the design, I make the statuette-pedestal A as an eight-sided or octangular prism; and I also give to the earth-holding pan B a like form, and arrange the two con-

centrically; and I give to the trellis C, which extends up from the pan, the pointed arched form and a configuration in other respects as shown.

The design which constitutes my invention includes the configuration of the pedestal, the pan, and the trellis, all substantially as represented.

I claim—

The design for a grape-arbor or "vinarium," herein described and shown.

CHARLES H. CRUMP.
